(57) **CLAIM**

The ornamental design for a shelf support, as shown and described.

DESCRIPTION

FIG. 1 is a perspective view of a shelf support in accordance with one embodiment, the optional mounting holes in the upright support portions of the shelf support are shown in dashed lines and form no part of the design.

FIG. 2 is a side view of the shelf support of FIG. 1 looking from the right side of FIG. 1, it being understood that the side view from the left side is a mirror image of the view shown in FIG. 2.

FIG. 3 is a top view of the shelf support of FIG. 1.

FIG. 4 is a front view of the shelf support of FIG. 1, it being understood that the rearview is hidden during normal use of the shelf support and the rear surfaces, which may be planar, form no part of the ornamental design.

FIG. 5 illustrates a bottom view of the shelf support of FIG. 1; and,

FIG. 6 is a perspective view of a shelf support of FIG. 1 shown in an alternative orientation to illustrate an alternative mounting position of the shelf support of FIG. 1.
